HEEL FOR BOOTS

Filed Aug. 25, 1930

Fig. 8.

Inventor
Basilio Bridi
By B. Slinger, Atty.

UNITED STATES PATENT OFFICE

BASILIO BRIDI, OF ZURICH, SWITZERLAND

HEEL FOR BOOTS

Application filed August 25, 1930, Serial No. 477,660, and in Switzerland March 11, 1930.

The invention relates to heels for boots or shoes being more particularly intended for embodiment in heels having leather, rubber or like tread elements.

5 The main object of the invention consists in the provision of novel means for detachably securing the tread elements in place to permit worn elements being readily removed and a new one inserted securely and with facility.

10 The invention consists in the combinations and arrangements of parts hereinafter described and claimed.

15 The invention will be best understood by reference to the accompanying drawing forming a part of this specification, and in which

Fig. 1 is a perspective view of a heel embodying my invention, the pad being removed.

20 Fig. 2 is a perspective view of the removable pad.

Fig. 3 is a cross-section on line III—III of Fig. 1 with the pad in its position,

25 Fig. 4 is a perspective view of a second embodiment of the heel according to my invention.

Fig. 5 shows the pad in a perspective view.

Fig. 6 is a section on line VI—VI of Fig. 4 with the pad in its position of use.

30 Fig. 7 shows another construction of the heel in a perspective view and partly in section.

Fig. 8 is a cross section thereof.

35 Figs. 9 to 12 illustrate another form of the heel with pad.

Fig. 9 is a side view of the heel body partly in section;

Fig. 10 shows the pad in a plan view;

40 Fig. 11 is the locking plate in a plan view and

Fig. 12 is a section thereof.

In the construction shown in Figs. 1 to 3 a plate 1 is rigidly fixed by nails 2 to the heel body 3. The two outer edges 4, 5 run parallel each other and are bevelled to form guides for a plate 6, attached to the heel pad 7. The plate 6 is rigidly fixed to the pad 7 by means of nails if the pad 7 consists of leather and is attached to the pad if the latter consists of rubber, by vulcanization, the plate being in

this case provided with extensions embedded in said rubber pad. The plate 6 is provided with two slots 8, 9 the edges 10, 11 are bevelled and adapted to engage the edges 4, 5 of plate 1. The part of plate 6 between the slots 8, 9 forms a springy tongue 12 having a tooth 13 at its free end. The tooth 13 engages a notch 14 at the fore end of the plate 1 and abuts against the face of the plate 1 in said notch. The tooth 13 is provided with an incision 15 and the plate 1 with a small notch 16. The pad 7 (Fig. 2) is pushed over plate 1, the plates 1 and 6 engaging each other until the tooth 13 passes into the recess 14. The pad 7 is thereby secured on the heel. To displace 65 the pad 7 a pointed tool is pushed into the incision 15 and the notch 16 whereby the parts 1 and 6 are driven apart and the tooth 13 is freed from its locking position in the recess 14. The pad 7 may be pushed back taken off 70 the heel body 3.

The device shown in Fig. 4 to 6 comprises an angular plate 20 of metal sunk into a recess of the heel body 21, and rigidly fixed thereto. On the plate 20 two raised guide pieces 22, 23 are fixed, the outer curved edges 24, 25 thereof being bevelled. The metallic frame 26 of the pad is provided with a recess 27, the curved edge 28 of which being bevelled too. The edges 24, 25, 28 engage each other, the frame 26 being held thereby on the heel body. To retain the pad 26 on the heel body 21 two spring members 29, 30 are fixed to the frame 26 each being provided with a hook 33 at its free end. The members 29, 30 are located within the recess 27 and the space 31 between the two guide pieces 24, 25. The hooks 33 pass over the recessed faces 32 of the said pieces 24, 25 firmly securing the frame 26, of the pad. By a suitable tool 80 passed into the recess 27 the two free ends 33 may be pressed against each other until the hooks 33 pass from the edges 32 and the pad may be removed by pushing the same backwards. The pad may be of leather, rubber or metal and pieces of said materials might be fixed to the frame 26 in any suitable manner. For instance pieces of leather or rubber may be placed in the recess 35 of frame 26. Heavy nails, etc., used in mountaineering 100

might be riveted in the said frame 26 or otherwise firmly attached thereto or may be made to form part of the frame 26.

Figs. 7 and 8 show a modified construction. A steel plate 40 is arranged in a casting 41 which is formed to pass over the guide pieces 24, 25, the beveled edges of frame 41 and pieces 24, 25 engaging each other. The frame 41 is provided with nails formed on the casting or riveted thereto, etc. The springy members 33 form parts of the steel plate 40, the latter being formed by stamping. A slot 45 serves for introducing a tool to bring the hooks 33 out of engagement and to free the pad.

Figs. 9 to 12 show another embodiment of my invention. The heel body 53 of metal or any hard material is provided with a recess adapted to receive the upper portion 52 of a pad 51, of circular shape. The part 52 is provided with teeth 54 projecting radially and being spaced at regular distances apart. A locking plate 55 is passed in a cross slot of the heel body 53, the said plate 55 embracing the reduced middle portion of the pad 51 closely and passing tightly under the teeth 54. The locking plate retains the pad 51 in its proper position on the heel body and is held by a springy member 56 which engages a recess in the heel body 53. Said member 56 secures the locking plate 55 against accidental displacement and prevents the loss of the pad 51. The latter may be covered by leather, rubber or any other material.

While I have illustrated and described the preferred form of construction for carrying my invention into effect, this is capable of variation and modification without departing from the spirit of the invention. I, therefore, do not wish to be limited to the precise details of the construction set forth, but desire to avail myself to such variations and modifications as come within the scope of the appended claim.

What I wish to claim and secure by the U. S. Letters Patent, is:—

A heel having a fixed heel body and a removable pad, a plate fitted in the pad and provided with a pair of forwardly extending spaced spring operated locking teeth provided with lugs on the outer sides of their free ends, said heel body having a pair of spaced guide pieces on its body, on which the pad is longitudinally slideable, to receive the locking teeth therebetween, and provided with oppositely extending shoulders for engagement by the lugs of the locking teeth, said pad having a recess in its upper side open at its front end to receive said guide pieces, the walls of said recess and the outer edges of said guide pieces being beveled, to cause said guide pieces to lock said pad in place.

In testimony whereof I affix my signature.
BASILIO BRIDI.
